UNITED STATES PATENT OFFICE.

JOSEPH O. PAQUET, OF LOS ANGELES, CALIFORNIA.

POSITIVE-ACTION ROTARY-VALVE PUMP.

Application filed July 21, 1924. Serial No. 727,225.

This invention relates to pumps and has for an object to provide a positive-action, deep well, rotary valve pump.

An additional object is to provide a low speed rotary pump designed to be bodily set in a deep well hole, and an object is to provide drive means whereby to eliminate friction of contact due to any weight of the pump shaft extension.

10 An object is to provide a rotary-valve, deep well pump of most simple form and compact parts most of which can be produced from round stock metal; an object being to provide a pump of such design and organization as to require but very little machine dressing or finishing.

Another object is to provide a pump of approximately cylindrical form so that it may be readily lowered in a naked or cased well hole. In this connection an object is to provide for the mounting of the pump as a unit and joint device between the usual suction pipe and the discharge tubing so that a pump of maximum size can be used 25 within the hole. That is, to provide a pump of such design that its working elements are of a size nearly equalling, in overall dimension transversely, the diameter of the hole or casing.

30 More objects and advantages will be made manifest in the following specification of an embodiment of apparatus of the invention shown in the accompanying drawing; it being understood that other modifications, variations and adaptations may be resorted to within the scope of the invention and the spirit thereof as here claimed.

Fig. 1 is a longitudinal section of an installed pump.

40 Fig. 2 is a section on line 2—2 of Fig. 1.

Fig. 3 is a bottom end view.

Fig. 4 is a section on line 4—4 of Fig. 1.

Fig. 5 is an end elevation of a rotary valve.

45 Fig. 6 is an end elevation of the central spacing ring or blade house.

Fig. 7 is an end view of a shaft coupling.

The present invention pertains to a type 50 of pump embodying a disc-like rotor 2 the cylindrical periphery of which has a suitable number, four here, of radial teeth or blades 3 which, preferably, have thickened bases 4 to obtain strength. At each end of the rotor is a gear 5; these parts being fast

on a stub shaft 6 having bearings in end 55 blocks 7—8 forming parts of the pump shell. These blocks are of circular form and are externally threaded at 9.

As here shown, the shell includes a central blade or blade house 10 lying between 60 spacer rings 11 which, with the blade house 10, are of about the same outside diameter as the end blocks of the shell; the whole forming a compact body of cylindrical form of maximum size to lower in a given well 65 hole.

For economic construction, the meeting end faces of the shell parts 7—8—11 are ground flat and smooth to meet tightly and are fastened by through bolts 12. 70

75 A set of twin discs 13 are disposed in peripheral contact with each other on the medial plane of the periphery of the rotor 2 and also tangentially in contact with said periphery (Figs. 1 and 2); these discs forming valves having shafts 14 in parallelism and being radial to the rotor shaft 6. The valve shafts have bushings 15 countersunk in seats therefor in the contiguous faces of shell parts 7—11, 8—11; these parts being 80 pocketed or cut out to receive the interposed valves.

85 The rings 11 surround the gears 5 and these are in mesh with bevel pinions 16 fixed on the shafts 14 so that the valves and the rotor are turned in unison and here timed two rotations of each valve to one of the rotor. The rings 11 are shown as overlapping the margins of the end faces of the rotor and so form a closed annular fluid 90 space in which sweep the teeth or blades 3, which run close to the house 10.

95 The rotor here has four blades 3 and to clear these at regular intervals the valves 13 have marginal pockets 17, which obviously are cut or machined out to closely intermesh, gear-fashion, with the rotor teeth.

Fluid flow into the shell is had through an inlet port 20 in the bottom 7 and its near ring 11, thence into the blade chamber in 100 house ring 10; the inlet being disposed on the side of the valves from which the blades run away, Fig. 3. Any blade running away from the valves causes a suction on its rear side and liquid is drawn into the space between the leaving blade and the valves. Liquid trapped between the blades is carried 105 around until it is brought adjacent to an

outlet port 21 in head 8 and its near ring 11. Since the contacting valves 13-13 block flow liquid is expelled at the outlet with positive force by blade 3 approaching the valves.

The pump has a discharge conduit 23 in the present case forming a pump tubing leading from the well hole in which the pump is submerged. The tubing includes a suitable number of sections coupled by collars 25 (one being shown). A collar is here threaded onto the threads 9 of the end block 8; this having a gland 26 through which extends the stub shaft 6, this having a squared end 6^a.

A feature of my invention consists of means for driving the pump shaft 6 without throwing any weight of the driving means on the running parts in the shell, thus reducing friction thereof and avoiding rapid wear which necessitates pulling the pump from the well for renewals. The drive means includes a drive shaft consisting of sections 28 having squared (or other non-circular) ends to match the sockets in the ends of reversible couplings 29, only one of which is shown. The coupling has a cylindrical body rotatively fitted in a bearing 30 which is provided in each collar 25.

Around the bearing are provided flow passageways 31 for liquid passing through the pump. Each socketed coupling 29 has a medial girdle 29^a with faced ends to bear on the upper ends of their coupling bearing which thus form supports as well as bearings of rotation. The weight of each shaft section is taken wholly by its lower coupling and bearing.

The lowermost coupling (of a series) receives the stub shaft end 6^a.

Since each section of the extension shaft is supported on its own collar-bearing there is no tension created in the string and as each section is detached or free from the next no binding tendency results from any disalignment of the shafting in a deep hole.

The sections of tubing 23 are joined by collars 25 in the lowermost of which the pump body is screwed, and on the lower end of the pump body is screwed the perforated suction pipe 33. The discharge tubing, the pump body and the suction pipe are of substantially the same diameter and for a given well hole will be of a diameter just small enough to freely pass into and from the hole. The diameter of the pump is practically determined by the over-all diameter of the rotor with its blades plus the thin blade house ring 10. Since I eliminate radial ports and projections and employ ports in the ends of the pump, it will be seen that I can place a pump, in a hole, whose diameter is close to that of the hole, thus obtaining maximum efficiency because of com-

pactness and structural design. Usually pump tubing screws up right-hand and I show, by arrows, a right-hand rotation of pump shaft and rotor so that torque of actuation tends to tighten up the joint.

It is obvious that a machine of this type is workable as a motor when fluid is supplied thereto under pressure as the driving medium.

What is claimed is:

1. A pump having a driving, vertical, sectional shaft and a coupling and bearing means for contiguous ends of the shaft sections, comprising a bearing-box, and a vertically disposed coupling rotatively journaled in the box against undue whipping when rotating and being supported by the bearing-box, and having socketed ends to receive the shaft ends freely and slidably and for driving one section by the other.

2. A pump having a vertical, axial shaft, and a collar on the pump body provided with a weight taking bearing for an extension shaft from, and for driving, the pump shaft, said bearing including a rotatively journaled coupling having a supporting portion on which freely rests the lower end of an upwardly extending shaft.

3. A pump of the rotary disc-valve and geared rotor type, having an axial shaft, a bearing means at one end of the shaft, an extension shaft and a coupling turnably fitted in said bearing for operatively connecting the two shafts without transmitting the weight of one to the other.

4. A pump of the rotary valve and geared rotor type, having an axial stub-shaft, a bearing at one end of the pump, and an extension shaft coupling resting on an end of said bearing and turning therein, and seating and receiving an end of the stub-shaft.

5. A pump of the rotary valve and geared rotor type, having an axial shaft, a bearing at one end of the pump, an extension shaft coupling resting on an end of and turning in said bearing, and engaging the axial shaft, and a collar attached to the pump and carrying the said bearing; the coupling having a rest receiving the extension-shaft end.

6. A pump having a vertical, projecting stub-shaft, an aligned extension shaft, a bearing to take the weight of the extension shaft, and a loose joint coupling device journaled in said bearing and operatively and loosely connecting the said shafts.

7. A pump having a rotor provided with radial blades, rotary valves cooperating with the rotor blades, a shell section around the rotor blades, and end shell sections having inlet and outlet ports to the ends of the shell; all of the sections being coaxial and both said ports being wholly within the peripheral line of the rotor shell section.

8. A pump having a rotor provided with

blades, rotary valves cooperating with the blades of said rotor, a plurality of cylindrical, coaxial sections having abutting end faces, the end sections having inlet and outlet ports both within the circumferential line of the pump, said sections being secured together and forming a substantially cylindrical shell enclosing the pump parts.

9. A pump having a rotor provided with blades, transverse rotary valves cooperating with the blades of said rotor and with each other, a cylindrical, coaxial sectional shell enclosing the running parts; the end sections of the shell having inlet and outlet ports both in the end faces of the shell, said end sections being externally threaded to form a coupling in a section and discharge line.

10. A pump having an axial vertical shaft, a shell having end sections with inlet and outlet ports, a collar on one end of the pump shell, a bearing supported by said collar and provided with a passageway therebetween for liquid passing through the pump, a coupling resting upon one end of and journalled in the bearing and fitting one end of the said shaft, and an extension, driving shaft supported by said coupling.

11. In combination with a vertical shaft pump, a drive means comprising a stub-shaft in the pump, an aligned extension shaft section, a cylindrical coupling member having sockets in its ends to fit the near ends of the said shafts for driving the one by the other and having an end-faced girdle, and a bearing in which the coupling is journalled

and on which the girdle rests to carry the weight of the vertical extension shaft.

12. In a rotary pump or motor, a casing, a disc mounted in the casing and having radial blades, and a rotary valve slotted to receive the blades and disposed on an axis perpendicular to the axis of the disc and geared thereto; said casing having passageways for inlet and discharge of fluid to and from the effective pumping parts.

13. In a rotary pump or motor, a casing, a disc rotor journalled in the casing and having radial, peripheral blades sweeping in a chamber therefor, parallel, rotative valves meeting across the rotor and being slotted to receive the passing blades, and gearing synchronizing the rotor and valves; the casing having passageways for inlet and outlet to the said chamber.

14. In a pump or motor, a rotor having peripheral blades, a cylindrical shell structure having a sectional portion surrounding the blades and overlapping the sides of the marginal portion of the rotor and being coaxial with the latter and coaxial casing end sections having pockets and shaft journals in the side walls of each pocket and having a central gear chamber, a rotary valve in each recess cooperative with said blades, an inwardly extended shaft end for each valve, gears fixed on said shafts and disposed in said chambers, and rotor gears meshing with the first named gears for timing the valves.

JOSEPH O. PAQUET.
